UNITED STATES PATENT OFFICE.

EDWARD E. NOWELL, OF MANCHESTER, NEW HAMPSHIRE.

MEANS FOR CONTROLLING THE TRAVERSE OF YARN GUIDES ON SPINNING MACHINES.

Application filed December 7, 1921. Serial No. 520,626.

To all whom it may concern:

Be it known that I, EDWARD E. NOWELL, a citizen of the United States, residing at Manchester, in the county of Hillsborough 5 and State of New Hampshire, have invented certain new and useful Improvements in Means for Controlling the Traverse of Yarn Guides on Spinning Machines, of which the following is a specification, reference being 10 had to the accompanying drawings.

This invention relates to spinning machinery and particularly to means for winding yarn upon a bobbin or yarn receiver in such manner that a preliminary winding 15 or bunch is first laid and then a main or surface winding is laid, the bobbins or cops so wound being used in the shuttles of automatic feeler-replenishing or feeler looms.

The general object of my invention is to 20 provide improved means for automatically changing from bunch winding to surface winding and automatically varying the length of the traverse during such winding.

Another and more special object is to simplify 25 the mechanism for this purpose and render it very compact so that it shall be relatively cheap to manufacture and install and shall take up very little room.

A further object is to provide a controlling 30 mechanism of this character which shall be capable of being applied to a large variety of spinning machinery and which may be used with any ordinary builder action and with any ordinary ring rail lifting 35 mechanism.

Still another object is to provide a mechanism in which the length of the traverse for forming the bunch may be easily varied.

Other objects will appear in the course of 40 the following description.

My invention is illustrated in the accompanying drawings, wherein:

Figure 1 is a front view of a portion of a spinning machine having my invention applied thereto;

Figure 2 is a section at right angles to Figure 1, showing the builder action;

Figure 3 is an elevation partly in section of a portion of the builder action and the members 27 and 34;

Figure 4 is a sectional view through the drum 27, the gear wheel 23 being partly broken away;

Figure 5 is a perspective view of the drum 55 27 and the member 34;

Figure 6 is an elevation showing the action of the device when the member 34 is shifted;

Figure 7 is a vertical sectional view of one of the spindles B; and

Figure 8 is a perspective view of the screw pin 39.

Figure 9, is a fragmentary view showing pin 39 in operative position.

Referring to these figures A designates the 65 spindle rail supported on a suitable frame and on which are mounted the rotatable spindles B. Coacting with these spindles is the reciprocating ring rail C provided with rings D, one for each spindle. These rings 70 are reciprocated by means of lifter rods F which engage with the ring rail and these lifter rods are operated by means of the rocker arms G which are angular in form to provide the upwardly extending arm H, 75 these arms being connected by a rod I in the usual manner and being pivoted each upon a pivot J and being each counterbalanced by a weighted arm K. All of these parts 80 may be of any ordinary or suitable construction. At the upper end of one of the arms H are disposed the bolts 10 having hooks at their extremities, these bolts being adjustable through the arm H.

For the purpose of oscillating the rocker 85 arms G and H to thereby cause the reciprocation of the ring rail, any ordinary builder action is used, and I have illustrated in Figure 2 a common form of such action, in which 11 is the builder arm which is pivoted at 12 and which carries at its inner end a drum 13. This drum is rotated in one direction by means of a worm 14 mounted upon a pick shaft 15 which carries upon it a pick wheel 16 adapted to be turned upon the 90 upward movement of the inner end of the arm by means of a pawl 17 and the usual vertically disposed rod 18 which passes through the frame of the machine and which is provided with a stop 19 which, when it 95 engages the frame, depresses the outer end of the pawl and turns the pick wheel a predetermined amount to rotate the drum 13 in an unwinding direction. The builder arm 11 is oscillated by means of a cam 20 of any 100 suitable or usual form. All of these parts are those commonly found in spinning machines of this character.

Mounted in a suitable bracket 21 attached to the frame is a shaft 22 which is preferably 110

fixedly mounted in the bracket. Loosely mounted upon this shaft is a gear wheel 23 and mounted and held from rotation on this shaft is a disk 24. The gear wheel 23 has upon its face confronting the disk 24 a plurality of ratchet teeth 25 and the disk 24 carries a plurality of coacting ratchet teeth 26. The teeth 25 and 26 together constitute a ratchet clutch. Surrounding the gear 23 and the disk 24 is a drum designated generally 27 which is formed in two sections. This drum is mounted to rotate with the shaft 22. A spring 28 surrounding the shaft 22 urges the gear wheel 23 toward the disk 24 so as to bring the clutch teeth 25 and 26 into engagement with each other. The section 29 of the drum is provided adjacent one point of its periphery with a passage in which is disposed a shaft 30, the inner extremity of this shaft being supported in a bearing 41 formed in the opposite section of the drum. This shaft, at one point in its length, is formed with gear teeth 32 meshing with the teeth on the gear wheel 23. The outer end of the shaft is formed with a socket 33 which is interiorly screw-threaded as at 33^a.

Loosely mounted upon the shaft 22 exteriorly of the section 29 of the drum is a segmental disk 34. This disk is formed with the circumferential face 35 and the end faces 36 and 37 which are disposed at an angle to each other, these faces 36 and 37 extending inward convergently and intersecting the face 38 of the hub of this disk 34. Carried upon the disk 34 is a pin 39 which projects inward beyond the inner face of the disk 34 and is provided upon one portion of its periphery with a plurality of interrupted screw threads 40 adapted to be engaged by the screw threads 33^a. This pin is engaged with the disk 34 in such manner that the disk and pin will move together. I have illustrated the pin as being connected to the disk by a transverse pin. As before remarked the disk 34 is loose upon the shaft 22, but is urged toward the drum by means of a coil spring 41, one end of which is engaged with the disk 34 while the other end is engaged with the collar 42 adjustably mounted upon the shaft 22.

Extending around the drum 13 and adapted to be wound up thereon or released therefrom is a chain 43 which extends upward and partly around the drum 27, the extremity of the chain being connected to the drum by means of the screw 44. Attached to the drum 27 by means of a screw 45 is a chain 46 which extends around the drum and then extends to and is operatively engaged with one of the hooks 10. Attached to one end of the disk 34 by means of a screw 47 is a chain 48 which passes around the circular circumference of the disk, then extends along the face 37 over the hub 38

and then tangentially to the other hook 10, the chains 46 and 48 being connected to these hooks by means of rings or shackles 49 of any suitable character.

The disk or member 34 is normally disposed in the position illustrated in Figure 1 and Figure 3, and under these conditions the chain 48 is taut while the chain 46 is slack. Now it will be obvious that motion communicated to the oscillating drum 27 will also be communicated to the disk 34, by reason of the fact that the pin 39 is engaged with the drum. Inasmuch as the chain 48 is at this time taut, it will be obvious that motion will be transmitted to the rocker arms H by means of the chain 48, and it will be also seen that as the end of this chain 48 moves in a path nearly parallel to the direction of the upwardly extending arms H of the rocker arms, but a very small motion of oscillation will be given to the rocker arms and this will continue so long as the disk 34 is positioned as illustrated in Figure 3. Upon the upward movement of the builder arm, the drum 27 will rotate in a clockwise direction. The gear wheel 23 being in mesh with the gear teeth on shaft 32, it follows that this gear wheel 23 will rotate with the drum by reason of the pressure of the spring 28 and its clutch teeth 25 will slip by the clutch teeth 26. Upon a reverse movement of the drum 37, however, the gear wheel 23 will be held from reverse rotative movement by the engagement of its clutch teeth 25 with the teeth of the fixed clutch 24, and as a consequence the teeth 32 meshing with the teeth 23 will cause a rotation of the shaft 30. This, through the screw-threaded socket, will act to shift the pin 39 outward and with the pin the disk 34 against the action of the spring 41. Thus upon each oscillation of the drum the segmental member 34 and the pin 39, which is fixed in the segmental member, will move outward against the force of spring 41 and eventually the pin 39 will be forced out of and disengaged from the screw-threads 33^a, whereupon the spring 41 will cause disk 34 to rotate from the position shown in Figure 3 to the position shown in Figure 6, that is with the face 37 of the disk 34 extending approximately vertically and the corner x of the member 34 will be coincident with the uppermost portion of the drum. This rotation of the member 34 will slacken the chain 48 so that this chain or flexible connection 48 will be thrown out of action and the motion of drum 37 will be communicated to the chain 46 and the rocker arm H.

The socket 33 is interiorly screw-threaded and the pin 39 has a coacting screw-thread, and as socket 33 revolves it will push the pin 39 and disk 34 outward against the force of spring 41, and when the pin 39 has

worked entirely out from socket 33, the bunch is then made and the chain 48 will then have no effect on the traverse of the yarn.

5 The pin 39 is threaded only on one side and the reason for this is that if it were threaded on all sides it would engage with the threads of the socket when the pin is being again inserted in the threaded 70 socket. The diameter of the pin 39 from the threaded side to the plain side is just small enough to permit the pin 39 to slip into the socket without interfering with the threads thereof. At this time the plain side of 75 the pin is against the threads, as will appear more fully hereinafter. Then as the frame is being started up after being doffed, the chain 46 will act to rotate the disk 27 and this will shift the disk 27 relative to the 80 sector-shaped member 34 a distance equal to the difference between the diameters of the pin 39 and the screw-threaded socket 40, and this will bring the threads of the socket against the threads of the pin 39 and the 85 pin will once more be in engagement with the threads on disk 34 and cause the threaded side of pin 39 to engage with the upper threaded side of the socket.

In Figure 7, I show a bobbin or yarn receiver 50 of a well known form. This has an enlarged base and an approximately cylindrical but tapering barrel. Near the head the barrel is made cylindrical to receive the preliminary winding or bunch of 90 yarn. The preliminary winding or bunch *a* is laid upon this cylindrical portion to the extent illustrated in Figure 7 and thereafter the winding is completed by the main or surface winding indicated by dotted lines. The 95 mechanism heretofore described is arranged to wind such a bunch and thereafter to lay the main or surface winding, the change from the bunch laying to the surface winding laying being automatic. The traverse is uniform during the winding of the bunch and uniform during the laying of the main winding, but the traverses is considerably shorter while the bunch is being laid than while the main winding is being laid, as is well understood by those skilled in the art. The gain 100 of the traverse is affected by the operation of the drum 13, the pick wheel 16 and the pawl 17 in the usual and well known manner.

The operation of the invention is as follows: At the start of the winding, the member 34 is in the position illustrated in Figure 4, and the pin 39 is fully inserted within the socket 33. With the member 34 in the position shown in Figure 3, the chain 105 48 is taut but the chain 46 is slack so that any motion communicated to the rocker arm H must come through the chain 48. It will be seen that the corner *a* constitutes practically the point of attachment of the chain 48 at this time and that the member 34 con- 110

stitutes practically an arm extending in a direction transverse to the direction of reciprocation of the lifter rods F. As a consequence, when the member 34 is oscillated by the oscillation of the drum through the 115 action of the builder action, the corner *a* will move toward and from the rocker arm H a relatively small amount so that a relatively short oscillation will be given to the rocker arms H. Step by step as these oscillations continue, the screw 39 will be shifted out until eventually it is disengaged from the socket 33 and at this time the bunch is completed. When the pin 39 has worked out from the socket the segmental disk 34 will move so that the pin 39 will be carried up slightly away from the socket. This slight movement of this segmental disk in the direction of the arrow (Figure 3) will slacken the chain 48 and as this chain no longer limits the oscillation of the arm H, the chain will no longer remain slack upon a clockwise movement of the drum 27 but will permit the rocker arms to shift to a greater range, thus increasing the traverse 120 of the spinning rings and the ring rail. The pull on the chain 48 with the parts in the position shown in Figure 6 tends to hold the pin 39 away from the socket. The end of the pin 39, however, drags on the cover 125 29 during the filling of the bobbins.

The collar 42 is so set as to give a twisting force on the segmental pulley or disk 34, while at the same time the spring urges the segmental pulley 34 or disk inward or 130 toward the cover 29. When the bobbin has been completely wound and is to be doffed, the ring rail is pulled down by the operator and, of course, the lifting rod F and the rocker G move down and when this is being 135 done the vertical arm H which carries the chain hook 49 moves in the direction of the drum 27 and thus the chain 43 moves downward with the builder arm 11. This causes the drum or disk 27 to turn in the same direction as the chain 43, or in other words to turn in a counterclockwise direction. The segmental pulley or disk 34 moves with the drum 27 in this direction, but not through the action of the chain 43 but only through 140 the twisting action of the spring 41. When the builder arm hits the floor, the chain 43 becomes slack and the drum 27 or disk does not turn any further. The segmental pulley 34, however, turns a little further 145 through the action of the spring 41 until the pin 39 comes opposite the socket 33^a. When the pin 39 comes opposite the socket, the spring 41 will urge the segmental pulley 34 with the pin fixed thereto inward or toward the drum 27 and the pin, of course, will slip into the socket and the parts are ready to repeat the operation. When the pin 39 is being inserted into the socket 33^a, the twisting action of the spring 41 keeps 150

the plain side of the pin 39 against the thread in the socket, thus permitting the pin to slip into the socket easily, the plain side of the pin resting against the thread of the 6 socket until the ring rail is let up, and when this is done the lifting rod F and the rocker G will raise and this will cause a pull on chain 48 and 46 and when this is done the threads in the socket 33^a will engage the 10 threaded part of the pin 39. Then as the gear and socket revolve, the pin 39, or rather its threaded portion, follows the thread of the socket until the pin has worked out through the socket and the bunch is completed. Then the operation heretofore described is repeated.

I am aware that mechanisms have been provided for the purpose of automatically controlling the traverse of the ring rail but 20 these mechanisms are relatively complicated, costly and occupy considerable room. This device is so simple that it may be cheaply made and occupies only a space of about two and one-quarter inches by four inches. 25 This bunch building mechanism will leave about three or four yards of filling on the bobbins compared with forty or fifty yards left on the bobbins by the ordinary builders. It is entirely automatic in its action and 30 may be easily set while the bobbins are being doffed.

While I have illustrated a form of my invention which I have found to be entirely practical and thoroughly effective in every 35 way, yet it is obvious that the principle of the invention may be embodied in various forms. Furthermore, it is obvious that the principle of the invention consists in providing a member (27) which is oscillated 40 through a predetermined stroke by the builder action and which is connected to the rocker arm, and providing a member pivoted concentrically to the first named member whose end furthest from the rocker arm is 45 connected to the rocker arm by means of a flexible connection, this second named member being locked to the first named member during a predetermined period so that its flexible connection will be taut, the second 50 named member being so disposed during this period that its end furthest from the rocker arm moves nearly parallel to the rocker arm and, therefore, gives but a slight motion to the rocker arm and thus limits the 55 oscillation of the rocker arm to a very small range. When this member 34, which in effect constitutes an arm whose end is at α and which is pivotally mounted upon the shaft 22, is unlocked from its engagement 60 with the member 27, it rotates freely to a position where the face 37 is disposed in a plane approximately parallel to the rocker arm H and thus has a relatively long movement horizontally with a relatively small 65 vertical component. This slackens the chain

48 and thereafter the full motion is given to the rocker arm H by the oscillation of the drum 27 and the projection and retraction of the connection 46.

Having described my invention, what I 70 claim is:

1. In means for controlling the traverse of spinning rings, a ring rail shifter, a builder action, an oscillatable transmission member operatively connected to the shifter, 75 means operated by the builder action for giving an oscillation to the transmission member equal to the amplitude of movement of the building action, a second oscillatable transmission member also operatively connected to the shifter, means for giving a less oscillation to this second named transmission member than to the other transmission member, said means being operatively connected to and driven by the builder action, 80 and means for rendering the second transmission member active and the first transmission member inactive during a predetermined period and then automatically rendering the second transmission member inactive and the first named transmission member active comprising a stop member carried by one of said transmission members 85 and engaging the other transmission member, the other transmission member having a socket to receive said stop member, means 90 yieldingly resisting movement of the transmission member from a neutral position, and means acting as the transmission members are oscillated to cause the stop member to shift little by little out of said socket to thereby detach the transmission members 95 from each other.

2. In means for controlling the traverse of spinning rings, a ring rail shifter, a builder action, an oscillatable transmission member operatively connected to the shifter, 100 means operated by the builder action for giving an oscillation to the transmission member equal to the amplitude of movement of the building action, a second oscillatable transmission member also operatively connected to the shifter, means for giving a less oscillation to this second named transmission member than to the other transmission member, said means being operatively connected to and driven by the builder action, 105 means for rendering the second transmission member active and the first named transmission member inactive during a predetermined period and then automatically rendering the second transmission member inactive and the first named transmission member active comprising a pin fixed on the 110 second named transmission member, the first named transmission member having a socket to receive said pin, means urging the second named transmission member against the first named transmission member to thereby 115 yieldingly hold the pin in said socket, said 120 pin being yieldingly urged into the socket by the second named transmission member, the 125 second named transmission member having a pin to receive said pin, means urging the second named transmission member against the first named transmission member to thereby 130 yieldingly hold the pin in said socket, said

means resisting movement of the second named transmission member toward a neutral position, and means acting as the first named transmission member is oscillated to cause the pin to shift little by little out of the socket to thereby detach the transmission members from each other.

3. A traverse controlling mechanism for forming yarn packages including a ring rail actuating rocker arm, a builder action including an oscillating lever, a drum, operative connections from the drum to the oscillating arm of the builder action and from the drum to the rocker arm, means for limiting the movement of the rocker arm during a predetermined period to thereby confine the reciprocations of the ring rail including a sector-shaped transmission member mounted concentrically to the drum, means for holding the sector-shaped member in engagement with the drum for a predetermined period while the package is being formed and then automatically releasing said sector-shaped member including a pin carried on the sector-shaped member, the drum having a screw-threaded socket in which said pin engages, the socket being larger than the pin and the pin having screw-threads on one face only, and a spring urging the sector-shaped member against the drum and yieldingly resisting movement of the sector-shaped member from a neutral position.

4. A traverse controlling mechanism for forming yarn packages including an oscillatory builder action, a reciprocatable yarn guide, a rocker arm operatively connected thereto, an oscillatory drum operatively connected to the builder action for coincident oscillation, a flexible connection between the drum and the rocker arm, a member concentrically mounted to the drum, a screw-threaded pin normally holding said member in engagement with the drum, a flexible con-

nexion extending from the rocker arm 45 across and above the axis of the drum and engaged with the end of said member, a screw-threaded member carried by the drum with which said screw-threaded pin is adapted to engage, and means actuated by 50 the oscillation of the drum for rotating said last named screw-threaded member in a direction to disengage the screw-threaded pin therefrom to thereby permit the independent rotation of the said concentric member 55 to a position to slacken the connection therefrom to the rocker arm and thereby permit the actuation of the rocker arm directly through the drum.

5. A traverse controlling mechanism for 60 forming yarn packages including an oscillatory builder action, a reciprocatable yarn guide, a rocker arm operatively connected thereto, an oscillatory drum operatively connected 65 to the builder action for coincident oscillation, a flexible connection between the drum and the rocker arm, a member concentrically mounted with relation to the drum for independent oscillation relative thereto, a screw-threaded pin carried by said member, 70 an interiorly screw-threaded shaft carried by the drum into which said pin normally engages, a gear wheel loosely supported within the drum and engaging said shaft, said gear wheel having a clutch face, 75 a clutch member mounted within the drum but held from rotation therewith and having clutch teeth engageable with the last named clutch face, and a flexible connection extending from the rocker arm across and 80 above the axis of the drum and engaged with the end of said last named member.

In testimony whereof I hereunto affix my signature in the presence of two witnesses.

EDWARD E. NOWELL.
